UNITED STATES PATENT OFFICE

JOHN ALBERT OSTENBERG, OF CAMPBELL, CALIFORNIA.

MAGNETO DRIVE FOR INTERNAL-COMBUSTION ENGINES.

1,115,729.

Specification of Letters Patent.

Patented Nov. 3, 1914.

Application filed November 24, 1913. Serial No. 802,716.

To all whom it may concern:

Be it known that I, JOHN ALBERT OSTENBERG, a citizen of the United States, residing at Campbell, R. R. No. 9, in the county of Santa Clara and State of California, have invented a new and useful Improvement in a Magneto Drive for Internal-Combustion Engines, of which the following is a specification.

10 My invention relates to an improvement in a magneto drive for internal combustion engines; and the particular improvements therein consist of certain novel parts and combination of parts, the separate features 15 of which will be specifically pointed out in the claims concluding this specification, in connection with the drawings illustrating the same.

The object of my invention is to cause the 20 magneto to produce a spark of sufficient intensity to fire the initial charge in starting when the engine is turned over slowly by hand or otherwise, and also to automatically retard the timing of the spark so as to 25 avoid accident from back-firing.

My invention will be described in detail 20 hereinafter and illustrated in the accompanying drawings, in which—

Figure 1 is a vertical section through the 30 magneto drive. Fig. 2 is a cross section on line A—A of Fig. 1. Fig. 3 is a sectional view through gear 5 showing the operating spring attached to the gear and collar. Fig. 4 is a side elevation of my 35 invention when the cam shaft is connected direct to the magneto shaft. Fig. 5 is a cross section on line B—B of Fig. 4. Fig. 6 is a cross section on line C—C of Fig. 4.

Referring now more particularly to the 40 drawings, wherein like reference characters indicate corresponding parts in all the views,—1 indicates the cam-shaft gear of an internal combustion engine, from which is driven cam shaft 2 which is turnable and slide- 45 able in bearing 3, said bearing being attached to frame 1^a. On the outer end of cam shaft 2 is keyed gear 4, the same meshing with gear 5 which is revolvable on armature shaft 6 which is held in place by bearings 7 and 8 50 in frame 1^a. Said armature shaft 6 is coupled together at 9, and thereby connecting with magneto 10, the same being fastened to frame 1^a in any suitable manner. Keyed to armature shaft 6 is collar 11 carrying 55 arms 12. To said collar 11 is fastened one end of spiral spring 13, said spiral spring

encircling armature shaft 6 and connecting at its outer end to gear 5, said gear having pins extending therefrom adapted to engage arms 12 as shown at 14, said gear 5 also having pins 15 projecting therefrom in the positions shown and for the purpose herein-after described. Projecting from gear 4 are pins 16 in their proper relative positions to pins 15 on gear 5. In frame 1^a is fastened stud 17. On the inner end of said stud and movable thereon is detent 18, having arms 19, 20, and 21, bent and formed as shown in the drawings, said detent being held steady in position by friction washer 22, and prevented from rotating too far by stop pins 23. Against the inner edge of gear 4 and resting on bearing 3 is a movable block 24. Said block 24 is moved back and forth by helical cam 25, the same being operated by lever 26 and shaft 26^a, and held in place by catch 27 and notched bar 28.

The operation of my invention is as follows:—Lever 26 has two positions; in its normal position block 24 is in the position shown in the drawing. When said lever 26 is thrown into the second position, helical cam 25 throws block 24 forward, thus advancing gear 4 with its pivots 16, and cam shaft 2. Said pins 16 thereupon alternately come in contact with arm 19 of detent 18. When one pin 16 strikes said arm 19, arm 20 of said detent is thrown forward and stops arm 12 of collar 11, and consequently stops the revolution of armature shaft 6. As gear 5 continues to revolve on armature shaft 6, spring 13 is wound up. At a predetermined period in the revolution of gear 5, pin 15 strikes arm 21 and thus throws arm 20 off of arm 12, whereupon spring 13 causes said arm 12 to jump forward to its original position against stop pins 14. Since arm 12 is a part of collar 11, which is keyed to armature shaft 6, armature shaft 6 is thus made to move forward so quickly as to produce a spark of sufficient intensity to fire the initial charge in starting when the engine is turned over slowly by hand or otherwise.

While Figs. 1, 2, and 3 show the preferred embodiment of my invention, I also show in Figs. 4, 5, and 6, an additional embodiment of my invention where the magneto is connected direct to the cam shaft without gears; the same reference numerals 110 being used as are used in Figs. 1, 2, and 3. In this embodiment, the cam shaft and the

magneto shaft are connected by a male and female clutch as shown at 29, allowing sufficient play for the sliding movement of the cam shaft and also for the quick forward rotation of the magneto shaft. Gears 4 and 5 are replaced by collar 30 upon which are shown pins 15 and 16, which operate arms 19 and 21 respectively, arm 20 operating in a notched collar 31 attached to the magneto shaft 6. Block 24 is operated by a lever 26, and has helical threads operated by helical threads in bar 28.

Having thus described my invention, what I claim as new and desire to secure by Letters Patent is:

1. A magneto drive for internal combustion engines, comprising a slideable driving shaft with means for shifting the same operatively connected thereto, an armature shaft and means for connecting said driving shaft and said armature shaft, a detent and tripping device adapted to be thrown into and out of action by the shifting of said driving shaft, and a spring positioned on said armature shaft, causing said arma-

ture shaft to rotate at a higher velocity for a part of its revolution when said driving shaft is thrown forward and said detent and tripping device is brought into action.

2. In a magneto drive for internal combustion engines, the combination of a slideable cam shaft and means of connecting said shaft with the armature shaft and magneto, a collar carrying arms, a spiral spring adapted to encircle said armature shaft and connect with a driving means, said driving means, having pins extending therefrom adapted to engage arms, a detent having arms bent and formed as shown, a friction washer, a movable block, a helical cam and means by which said helical cam and said block are operated, substantially as shown and described.

In testimony whereof I have hereunto set my hand in presence of two subscribing witnesses.

JOHN ALBERT OSTENBERG.
